6 Claims

ABSTRACT OF THE DISCLOSURE

The present invention relates to synthetic oils which are tertiary-alkylated benzene and -naphthalene, wherein the tertiary alkyl substituents contain from 7 to 44, preferably an average of from 14 to 44 carbon atoms. The compositions have utility as hydraulic oils, as lubricants, and in the formulation of greases.

The tertiary alkyl-benzenes and -naphthalenes have higher boiling points and lower viscosities than the natural petroleum oils of the same average number of total carbon atoms, thereby providing a superior product where low volatility and high flash point at a given viscosity are required. The substantial absence of a hydrogen atom on the carbon alpha to the benzene ring makes the compositions of the present invention much superior in oxidation and thermal stability as compared to the primary and secondary alkyl benzenes and natural petroleum oils which are available.

The present invention relates to synthetic oils for use in a number of services, such as hydraulic oils, lubricating oil base stocks, base stocks for grease formulation, etc. The compounds have a higher boiling range and higher flash point than oils of the same viscosity which are from conventional processing of petroleum. Further, the compounds of the present invention are much more resistive to oxidation and thermal degradation than primary and secondary-alkylated aromatics since they do not possess significant amounts of benzylic hydrogens (a hydrogen atom on the alpha carbon to the benzene ring). They are also superior to conventional petroleum oils with respect to these characteristics.

The compounds of the present invention are predominantly tertiary alkylated-benzene and -naphthalene. Benzene may be either mono or disubstituted, whereas naphthalene will be mono or higher substituted.

The composition of the present invention consists essentially of one or more compounds which correspond to the structural formula:

wherein

R₁, R₂ and R₃ are alkyl groups,
R₄ is hydrogen or a t-alkyl group,

A is benzene or naphthalene, and the total number of carbon atoms in all substituents attached to A is from 7 to 44.

The composition contains less than about 40 weight percent, preferably less than about 15 weight percent, of compounds possessing benzylic hydrogen atoms. Where A is naphthalene, R₄ is hydrogen, usually.

The compositions may, if desired, be hydrogenated to saturate the aromatic nucleus. In such case, A will be a naphthenic radical.

The total number of carbon atoms in alkyl substituents, whether in a single substituent or in two substituents, will range from 7 to 44, preferably from 14 to 44. The dialkyl-

2

benzenes, because of their higher viscosity, are particularly suitable for grease formulations, whereas the monoalkyl-benzenes are particularly useful in lubricating oil and hydraulic oil service; however, t-alkyl benzenes may be used as grease base oils where the t-alkyl group contains enough carbon atoms (e.g., 27 carbon atoms). Exemplary compounds for various uses are C₁₆H₃₃ t-alkyl benzene (hydraulic oil for low temperature service), C₂₁H₄₃ t-alkyl benzene (lube oil), and C₂₇H₅₅ t-alkyl benzene (grease base oil). In each of the above examples, the carbon and hydrogen amounts refer only to the t-alkyl substituent and do not include those in the benzene nucleus. The numbers represent the average carbon and hydrogen content of the substituents.

15 The compounds of the present invention are prepared by the method disclosed and claimed in copending application Ser. No. 101,921, entitled "Selective Tertiary Alkylation of Aromatic Hydrocarbons" by Jesse K. Boggs, filed on an even date herewith, the disclosure of which is incorporated into this application by reference. In that copending application, it is disclosed that the tertiary alkylation of aromatic hydrocarbons, utilizing bulky tertiary alkyl substituents, can be accomplished with selectivity and high yield only if a tertiary alkyl halide is used as the 20 alkylating agent and only if the evolved hydrogen halide is rapidly removed from the reaction zone, e.g., by operating under substantially reduced pressure.

25 As will be hereinafter more fully spelled out, a large number of synthetic oils have been prepared by the process of the copending application. These compositions are superior in oxidation resistance and in the resistance to thermal degradation.

GENERAL

30 The compositions of the present invention are useful as lubricants (oils and greases) and as hydraulic oils. The particular compound or mixture of compounds will be chosen to meet the needs of the specific use to which the product will be put. For lubrication service, the average number of carbon atoms in substituent groups will be from 14 to 44. When it is desired to obtain the lowest viscosity for a given boiling range, benzene will be the nucleus. Generally, the lower to middle range viscosity (i.e., from 2 to 6 cs. at 210° F.) alkyl benzenes will be 35 used as a lube oil base stock, while high viscosity (e.g., greater than 6 cs. at 210° F.) will be used as grease bases. The viscosity index (VI) improves as one R group of the t-alkyl substituent becomes longer, but the pour point also increases. For some uses (e.g., as a textile lubricant) 40 the VI and pour point are not critical—the low volatility for a given viscosity exhibited by these compounds is the desideratum. For other uses, such as automotive engine lubricants, the VI and pour point are important and are balanced off by selecting a proper tertiary-alkylated compound (or, usually, mixture of compounds) prepared in 45 accordance with the present invention. The pour point is reduced by using a mixture of compounds rather than a single, pure compound.

50 The compounds of the present invention exhibit a lower volatility for a given viscosity and a better balance of viscosity and boiling point for a given number of carbon atoms as compared to prior art lubricant compositions.

OLEFINS SUITABLE AS HALIDE SOURCES

55 The t-alkyl benzenes and naphthalenes of the present invention are obtained by alkylating the aromatic nucleus with a suitable t-alkyl halide. A preferred source of t-alkyl halides is the product obtained by hydrohalogenation of the mixed 2-alkyl-1-alkenes produced by dimerization of α -olefins of differing carbon numbers. The resulting mixture of t-alkyl halides provides alkylated aromatic

hydrocarbon mixtures of superior viscosity, viscosity index and pour point characteristics. Where a single α -olefin is used as a dimerization feedstock, the resultant olefin product is substantially pure and, where a single t-alkyl aromatic hydrocarbon is desired as a product, this approach will be taken in securing the alkylating agent.

In any event, the dimerization is carried out in the presence of a suitable catalyst, such as diisobutyl aluminum hydride $[Al(isobutyl)_2H]$. For example, from about 0.5 to 5.0 weight percent of diisobutyl aluminum hydride in the α -olefins forms the reaction mixture at elevated temperatures (e.g., 250° F. to 450° F.) and modest pressure (e.g., 0 to 100 p.s.i.g.) for 1 to 30 hours. The reaction proceeds as follows:

when heated during distillation and/or in an acid system (Al_2O_3 or HCl), the olefin product isomerizes:

In either case, the product upon hydrochlorination would be the same,

the tertiary chloride alkylating agent.

For convenience in discussing the structures of the tertiary halides, the number of carbon atoms in the R group around the central carbon atom are referenced by the corresponding numerals as shown below:

Example

4-1-12 structure

ALKYLATION

The desired nucleus (preferably benzene) is selectively t-alkylated by reaction with the selected t-alkyl chloride, using the method described in the copending application hereinabove referred to. In general, the reaction will be carried out at 0 to 30° C., 5 to 150 mm. Hg absolute, and in the presence of a rapidly boiling liquid. The benzene (or benzene-solvent mixture) can be maintained in an ebullient state and serve as the boiling liquid by suitably balancing the ratio of low-boiling solvent to benzene, and the reaction temperature and pressure. A Friedel-Crafts catalyst (preferably $FeCl_3$) is used to promote the alkylation reaction. The HCl which is evolved is rapidly removed from the reaction zone to minimize the formation of undesirable secondary alkyl isomers.

EXAMPLES

In order to illustrate the production of the compositions of the present invention, the following examples are given. In most of these examples, the reaction was carried out in a three-neck, 250 ml. flask, connected to a reflux condenser and bubbler and also to a source of controlled vacuum, with a dropping funnel being provided for the introduction of a liquid feed. The reaction flask was provided with a thermometer, a magnetic stirrer and a cooling bath. In the examples, the Friedel-Crafts catalyst in the aromatic hydrocarbon was charged to the flask, while additional aromatic hydrocarbon (or cosolvent) was introduced along with the tertiary alkyl chloride. The flask contents were chilled to a suitably low temperature, the pressure adjusted at the suitable pressure, and the contents of the dropping funnel added over a relatively long time period (e.g., 20 minutes). The temperature was

held within the desired range and the reaction products withdrawn in the vapor phase to the controlled vacuum line. The reaction products (mainly HCl) and volatilized liquid (aromatic hydrocarbon or cosolvent) were removed at a rate sufficient to maintain the hydrogen halide concentration in the liquid phase at the indicated level. A stripping period at even further reduced pressure was usually employed at the end of the vacuum runs. In some runs, where atmospheric pressure was employed, the vacuum was not drawn and the reflux condenser was allowed to reach equilibrium with the outside air.

Example 1

Alkylation of benzene with 3-chloro-3-ethylpentane (2-2-2) using conventional alkylation conditions. This example shows that the use of atmospheric pressure is unsuitable with $AlCl_3$, leading to the formation of nontertiary alkyl product, even when using a C_7 t-alkyl chloride.

A 5-liter flask in a water bath was used for this example, and it was equipped with five outlets for a calibrated dropping funnel, a thermometer, an inlet for liquid butane, a vent tube, and a magnetic stirrer.

The pot was charged with 585 g. of prechilled dry benzene, 13 g. of anhydrous $AlCl_3$, and 598 g. of butane. The dropping funnel was charged with 135 g. of 3-chloro-3-ethylpentane and 585 g. of dry benzene. The contents of the dropping funnel were added over a period of 1.6 hours and the temperature in the flask allowed to rise from an initial 7° C. to about 28.5° C. The pressure was 760 mm. Hg. After completion of the reaction, the product was water washed and the butane and benzene stripped from the reaction product. Gas chromatographic and NMR analyses were then carried out to determine that the yield was 83% of alkylate but that over 99% of the product was nontertiary in structure.

Example 2

Alkylation of benzene with 2-chloro-2-methylhexadecane (1-1-14) chloride using ferric chloride as a catalyst. The flask was charged with 1.6 g. of ferric chloride (anhydrous) and 24 g. of dry benzene. The dropping funnel was charged with 24 g. of dry benzene and 28 g. of the (1-1-14) chloride. The flask contents were chilled to about 5° C., pressure adjusted at 60-75 mm. Hg and the contents of the dropping funnel added over a period of 20 minutes. The temperature was held at 3-7° C. and the reaction proceeded very rapidly as shown by vigorous boiling and the evolution of HCl gas through the bubbler. After the chloride was added, 5 g. of additional benzene were added and conditions maintained for a further 40 minutes. After this time, the pressure was reduced to about 20-30 mm. Hg and held for 15 minutes to strip the reaction liquid phase of remaining volatile components. The contents then were poured over an ice-salt mixture to terminate the reaction. After working up the product by three (aqueous) saturated $NaCl$ washes (100 ml. each) and filtering, the benzene was removed on a rotating evaporator. The yield of stripped product was 29.4 g. Examination of a sample of the stripped product by nuclear magnetic resonance (NMR) showed nearly complete tertiary alkylation with no measurable hydrogen atoms alpha to the ring. The calculated maximum HCl concentration during the reaction was 0.00287 mol fraction (mol HCl per mol of solution). This was calculated on the Antoine equations for HCl and benzene, corrected for the solubility of HCl in benzene. At atmospheric pressure and the same temperature, the calculated HCl concentration would have been 0.0529 mol fraction.

Example 3

Alkylation of benzene with 2-chloro-2-methylhexadecane (1-1-14) using $AlCl_3$ as a catalyst. The flask was charged with 24 g. of dry benzene and 1.3 g. of anhydrous aluminum chloride. The dropping funnel was charged with 24 g. of dry benzene and 28 g. of (1-1-14) chlo-

ride. The flask contents were chilled to 6-10° C., the pressure adjusted to 50-60 mm. Hg absolute, and the contents of the dropping funnel added over a period of 21 minutes. The reaction was held an additional 55 minutes at a pressure of 50-60 mm. Then full house vacuum (20-30 mm.) was applied and held for an additional 15 minutes. The product was worked up as in Example 1 and 26.1 g. of yield were obtained. The maximum HCl concentration during the reaction was calculated at 0.00450 mol fraction. Under the same conditions at 760 mm., the concentration would have been 0.0488 mol fraction.

The product was examined by NMR and found to contain only 16% nontertiary alkylbenzenes and 84% desired tertiary alkylbenzene.

Example 3 illustrates that aluminum chloride can be used as a catalyst under our preferred conditions, with only a small amount of undesirable isomerization occurring.

Example 4

This example shows that with FeCl_3 benzene cannot be successfully alkylated with the C_{17} (1-1-14) olefin rather than the (1-1-14) chloride. The flask was charged with 24 g. of dry benzene and 1.6 g. of FeCl_3 (anhydrous). The dropping funnel was charged with 24 g. of benzene and 24 g. of the (1-1-14) branched olefin. The flask and its contents were held with stirring at atmospheric pressure and 10° C. while the benzene/olefin mixture in the dropping funnel was added over a period of 20 minutes. The ice bath was removed and the flask warmed to room temperature (25° C.) for an additional hour. One milliliter samples were taken at 15, 30 and 45 minute intervals after the start and at the end of the reaction. After 1 hour and 20 minutes, the reaction mixture was poured over an ice-salt mixture, separated and washed three times with 100 ml. of a saturated NaCl aqueous solution. It was paper filtered and benzene removed on the rotating evaporator. A yield of 21.6 g. was obtained, but gas chromatograph data showed no alkylation product in any of the samples.

Example 4 illustrates that with FeCl_3 tertiary alkylation with the olefin cannot be carried out directly, but that the use of the alkyl halide is necessary.

Example 5 (dialkylation)

This example shows the alkylation of benzene with two tertiary alkyl groups. The procedure of Example 5 was similar to that of Example 1, but was carried out in two steps and in equipment which was larger than that used in Example 1. In step 1, 1560 g. of dry benzene and 24.3 g. of FeCl_3 (anhydrous) were charged to the flask while

previously described. The product was distilled to recover the tertiary amylobenzene overhead (yield 387 g.) and this was used as the charge for the second step. Under the conditions employed, the maximum HCl concentration was about 0.0277 mol fraction as compared to 0.0515 mol fraction which would have been present at 760 mm. About 90% of the feed chloride was converted to give a mixture of about 2.6 mols of crude monotertertiary amylobenzene and 0.14 mol of crude ditertiary amylobenzene.

10 119 g. of the tertiary amylobenzene from step 1 and 5.7 g. of FeCl_3 (anhydrous) were charged to the flask. The dropping funnel was charged with 176 g. of 2-chloro-2-methyltetradecane (1-1-12). The alkyl chloride was added over a period of 1 hour to the flask which was maintained under a temperature of 0 to 5° C. and a pressure of 40 mm. Hg absolute. It was held for an additional hour under those conditions and the temperature then raised to 20° C. for 15 minutes and the pressure thereafter reduced to 15 mm. Hg for an additional 20 minutes. The product was worked up and examined to determine the nature of the product. Only about 15% of the product contained a hydrogen atom alpha to the ring.

15 Although some isomerization did take place with the heavier fractions, the alkyl attachments remained predominantly tertiary. This is true even in the bottoms fraction recovered from step 1 where the maximum nontertiary attachment was seen to be 15% by NMR examination. The calculated maximum HCl concentration in the second step was 0.00349 mol fraction as compared to 0.0585 for the same alkylation if conducted at 760 mm. Hg pressure.

20 The di-*t*-alkyl product was of the formula:

30 This example shows the production of a dialkyl benzene having no hydrogen atoms alpha to the ring.

Examples 6 through 14

40 Following the same general procedure as above described, a number of other runs were made with different alkylating agents and with different Friedel-Crafts catalysts. The results of these runs are tabulated below in Table I, wherein the alkylating agent is identified by the number of carbon atoms in R_1 , R_2 and R_3 .

45 Table I illustrates that tertiary alkylation of benzene has been accomplished in good selectivity so that the product is the improved synthetic oil of the present invention.

TABLE I.—ALKYLATION OF BENZENE WITH TERTIARY ALKYL CHLORIDES

Example number	Alkyl agent	Catalyst	Press., mm. Hg ¹	Max. HCl mol fract.	Reaction time, hrs. ²	Temp., °C.	Conversion, mol percent	Selectivity, percent
6	2-2-2 Cl	FeCl_3	28	0.00142	1.7	0	84.8	>95

14	9-1-10 Cl	$(\text{AlCl}_3 \cdot (\text{FeCl}_3)_3$	62-95	0.00455	0.8	10-25	97	66.4

¹ Usually finished at lower pressures.

² In stages (a) time of addition (0.5 to 1 hr.), (b) holding (1 hr.), (c) finishing (0.5 hr.). Times given in parentheses are those usually employed.

³ In the actual run, some olefin was present; this conversion is calculated on the basis of tertiary alkyl chloride concentration.

1560 g. of dry benzene and 342 g. of 2-chloro-2-methylbutane (1-1-2) were charged to the dropping funnel. The contents of the funnel were added over a 2 hour period, while the flask was maintained at 7-8° C. and 400 mm. pressure. Thereafter, the contents were held at 1.5 hours at the same temperature and pressure. After 3.5 hours, the pressure was reduced to 100 mm. Hg and held for 15 minutes. The reaction was terminated by pouring the mixture over an ice-salt mixture and worked up as

70 Referring particularly to Table I, it should be noted that the selectivity of the alkylation reaction has been greater than 95% in almost every instance under our most preferred conditions, and in those instances where secondary alkyl groups have been formed, they have not been in such quantities as to be unduly deleterious to the final product.

In the cases of Examples 7, 11 and 14, however, where a considerably lower selectivity was encountered, it is to

be noted that a higher purity product could have been obtained by a suitable selection of reaction conditions. For example, Example 7 showed a selectivity in some boiling ranges as low as 86%. These compounds can be separated by distillation for the recovery of the high purity product or conditions similar to those shown in Example 12 could be employed for high selectivity (i.e., the pressure could be reduced to 40 mm.). Similarly, in Example 11, the pressure could be reduced for an improvement in selectivity. In Example 14, where a hybrid

catalyst was employed, the use of the catalyst and procedure of Example 13 raises the selectivity to >95%.

Thus it is seen that the present invention relates to mono- and di-*t*-alkylbenzenes having widely varying carbon numbers in the alkyl group.

The compounds produced by alkylation of benzene are shown below by structural formula, together with the viscosity thereof where such measurement is available. The viscosity in those instances is compared to the viscosity of a normal alkyl benzene.

TABLE II.—STRUCTURAL FORMULAS

Example 15

Alkylation of naphthalene with 3-chloro-3-ethylpentane (2-2-2) using cyclohexane solvent. The flask was charged with 100 g. of cyclohexane solvent, 25.6 mols of naphthalene, and 1.6 g. of FeCl_3 (anhydrous). The dropping funnel was charged with 13.5 g. of the (2-2-2) chloride. The addition was carried out over a period of 0.3 hour, and to the flask which was maintained at 20° C. and 65 mm. Hg. The reaction was held for an additional 3 hours under the same conditions, and then for a half-hour at 20-30 mm. Hg. The product was worked up and found to contain no measurable benzylic hydrogen (a hydrogen atom alpha to the aromatic ring). Thus, by reducing the pressure and using cyclohexane as a boiling liquid, selective alkylation was accomplished.

The product had the structural formula:

Example 16

Alkylation of alpha methyl naphthalene with 3-chloro-3-ethylpentane (2-2-2) using cyclohexane solvent. A run similar to Example 15 was made using 40 g. of cyclohexane, 28.4 g. of alpha methyl naphthalene and 1.6 g. of FeCl_3 (anhydrous) in the flask, with 13.5 g. of 3-chloro-3-ethylpentane (2-2-2) in the dropping funnel. The addition was carried out over 0.13 hour, the flask being maintained at 22° C. and 65 mm. Hg. The reaction was held under those conditions for an additional 3 hours and then for 0.5 hour at 20-30 mm. Hg. After a workup of the product, the NMR analysis showed 65.2% alkylation based on the tertiary chloride. Ninety percent of the product was 3-ethyl-3-naphthylpentane and nearly 10% 3-methyl-3-naphthylpentane with possible traces of 2-methyl-2-naphthylpentane. It is to be noted that although the tertiary alkyl group isomerized, the product was still a tertiary alkyl. No measurable quantity of benzylic hydrogen was found in the alkylated product. The maximum HCl concentration during alkylation was calculated to be 0.00034 mol fraction.

The primary product has the structural formula:

This example shows that α -methyl naphthalene, as well as naphthalene, can be selectively alkylated with the present process.

Example 17

Alkylation of t-butylbenzene with 3-chloro-3-methylpentadecane (2-1-12) in the presence of triethylamine. The flask was charged with 114 g. of t-butylbenzene, 24.3 g. of anhydrous iron chloride, and 8.6 g. of triethylamine. The dropping funnel was charged with 14 g. of t-butylbenzene and 221 g. of 3-chloro-3-methylpentadecane (2-1-12). The addition was carried out for a total of 1.5 hours, while the flask was maintained at a temperature of 12-36° C. and 40 mm. Hg. The reaction was held under those conditions for an additional hour and then the pressure was reduced to about 15 mm. Hg and held for about 0.5 hour. The product was worked up and found to represent a 24% molar yield based on the tertiary chloride. Only traces of benzylic hydrogen were discovered by NMR analysis, indicating that tertiary alkylation without isomerization to nontertiary forms had been obtained. It was noted that considerable interchange of alkyl groups had taken place, the highest boiling fractions

5

containing large amounts of di(3-methylpentadecyl)benzene:

Example 18

The following examples are directed to alkyl benzenes having one or two alkyl substituents. The alkyl substituents were obtained by dimerizing α -olefins and then reacting the dimerization product with HCl. The α -olefins employed were C_6 - C_{14} (even-numbered), in admixture or alone.

The resultant t-alkyl chlorides were reacted with benzene, using FeCl_3 as a catalyst and employing the techniques more particularly described in copending application Ser. No. 102,921, "Selective Tertiary Alkylation of Aromatic Hydrocarbons" by J. K. Boggs and filed on an even date herewith. After completion of the alkylation reaction, the products were separated by distillation.

The following dimerization products were obtained from an admixture of C_6 , C_8 , C_{10} and C_{12} α -olefins:

	C_{18}	C_{20}	C_{22}	C_{24}
25	1 4-1-12	1 4-1-14	1 4-1-16	-----
30	1 6-1-10	1 6-1-12	1 6-1-14	-----
35	1 8-1-8	1 8-1-10	1 8-1-12	1 8-1-14
	-----	10-1-10	10-1-12	-----

From these olefins, the corresponding t-alkyl chlorides were obtained by hydrochlorination.

The admixture of alkyl chlorides was reacted with boiling benzene in the presence of FeCl_3 catalyst and under a vacuum to obtain a mixed t-alkyl benzene product. During alkylation, some desirable rearrangement by methyl shift may occur; e.g., from the

halide, the

t-alkyl aromatic structures may also be obtained as well as the expected

60 t-alkylated aromatic. The product exhibited an alkyl-substituent carbon number distribution as follows:

	Mol percent
$\emptyset\text{C}_{14}$	Nil
$\emptyset\text{C}_{16}$	1.0
$\emptyset\text{C}_{18}$	15.1
$\emptyset\text{C}_{20}$	32.6
$\emptyset\text{C}_{22}$	32.3
$\emptyset\text{C}_{24}$	19.0
$\emptyset\text{C}_{26}$	-----
	100.0

The symbol $\emptyset$ indicates benzene nucleus; hydrogen quantities are omitted.

75 The mixed product was suitable as a synthetic lubricant.

11
Example 19

Benzene was alkylated with a mixture of tri-substituted ethylene type C_{21} isoleolefins and the corresponding tertiary alkyl chlorides. The olefin mixture was made up of 34 mol percent of 10-methyleicosene-9, 51 mol percent of 10-methyleicosene-10, and 15 mol percent of 2-nonyldodecene-1:

The tertiary alkyl chloride is derived from the mixture of three olefins, and has the structure:

10-chloro-10-methyleicosane

An admixture of 239 g. of the olefin mixture and 258 g. of the alkyl chloride plus 293 g. of benzene was added to 293 g. of benzene and 5 g. of AlCl_3 over a period of 60 minutes while stirring the liquid reaction mass. The temperature varied from 5° C. to 15° C. during the reaction period. A vacuum was maintained, the pressure during the reaction being about 60 mm. Hg absolute. After termination of the reaction the product was recovered and found to have the following analysis:

Tertiary alkyl benzene	64
Secondary alkyl benzene	36
Primary alkyl benzene	0

The product was compounded to produce an aviation hydraulic fluid having the characteristics shown in Table III below.

TABLE III.—AVIATION HYDRAULIC FLUID ^{a, b}

Synthetic oil

^a Blended as follows: Synthetic oil, 98 wt. percent; Tricresyl phosphate, 1 wt. percent; Antioxidant (ethyl 702), 1 wt. percent.

^b The finished blended oil may also contain VI improver and pour depressants as desired.

^c As determined by MIL-H-27601A.

Example 20

Benzene was alkylated with a mixture of internal C_{17} isoolefins and the corresponding tertiary alkyl chloride. The olefin mixture was made up of 32 volume percent of 6-methylhexadecene-5 and 68 volume percent of 6-methylhexadecene-6:

The tertiary alkyl chloride is derived from both of the above-mentioned olefins and has the structure:

An admixture of 139 g. of the olefin mixture, 274 g. of the alkyl chloride, and 293 g. of benzene was added as

12

the alkylating mixture to 293 g. of benzene and 5 g. of aluminum chloride over a period of 60 minutes while stirring the liquid reaction mass. The temperature varied from 5° C. to 15° C. during the reaction period. A vacuum was maintained, the pressure during the reaction being about 60 mm. Hg absolute. After termination of the reaction, the product was recovered and found to have the following analysis:

	Percent
10 Tertiary alkyl benzene	69
Secondary alkyl benzene	31
Primary alkyl benzene	0

The product was compounded to produce an aviation hydraulic fluid having the characteristics shown in Table IV below.

	Synthetic oil
20	$\begin{array}{c} \text{CH}_3 \\ \\ \text{C}_6\text{H}_{11}-\text{C}-\text{C}_{10}\text{H}_{21} \\ \\ \text{C}_6\text{H}_5 \end{array}$ (Example 20)
15	$\begin{array}{c} \text{CH}_3 \\ \\ \text{C}_6\text{H}_{11}-\text{C}-\text{C}_{10}\text{H}_{21} \\ \\ \text{C}_6\text{H}_5 \end{array}$ (Example 19)

^a Blended as follows: Synthetic oil, 98 wt. percent; Tricresyl phosphate, 1 wt. percent; Antioxidant (ethyl 702), 1 wt. percent.

^b The finished blended oil may also contain VI improver and pour depressants as desired.

^c As determined by MIL-H-27601A.

40 We claim:

1. A composition useful as a lubricant and consisting essentially of an admixture of monosubstituted tertiary alkyl benzenes in the approximate proportions:

	Mol percent
55 $\text{C}_{16}\text{H}_{33}$ t-alkyl benzene	1.0
$\text{C}_{18}\text{H}_{37}$ t-alkyl benzene	15.1
$\text{C}_{20}\text{H}_{41}$ t-alkyl benzene	32.6
$\text{C}_{22}\text{H}_{45}$ t-alkyl benzene	32.3
$\text{C}_{24}\text{H}_{49}$ t-alkyl benzene	19.0

wherein the carbon and hydrogen amounts represent the average quantities in the respective t-alkyl substituents.

55 2. A process which comprises

- (1) dimerizing an α -olefin in the presence of diisobutyl aluminum hydride at a temperature from about 250° F. to about 450° F. and a pressure from about 0 p.s.i.g. to about 100 p.s.i.g.;
- (2) hydrochlorinating the dimerization product; and
- (3) alkylating an aromatic nucleus with said hydrochlorinated internal olefin, under conditions including:

an effective amount of a Friedel-Crafts catalyst, a temperature from -10° C. to +30° C., a pressure from 20 to 150 mm. Hg absolute, and in the presence of an ebullient liquid, said conditions being correlated so as to remove HCl from the reaction zone at a rate sufficient to minimize the formation of undesirable secondary alkyl isomers.

- 65 3. A composition consisting essentially of one or more compounds having the formula:

13

wherein:

- A is benzene or naphthalene,
 R₄ is hydrogen or a tertiary alkyl group,
 R₁ is methyl,
 R₂ is a C₁₀ or a C₉ alkyl group, and
 R₃ is a C₈ to C₁₄ alkyl group.
 4. A composition according to claim 3 wherein R₂ is C₉ alkyl and R₃ is C₁₀ alkyl.
 5. A composition according to claim 3 wherein R₁ is C₈ alkyl and R₂ is C₁₀ alkyl.
 6. A composition according to claim 3 wherein R₁ is C₉ alkyl and R₂ is C₉ alkyl.
